UNITED STATES PATENT OFFICE

117,980

DESIGN FOR A GLASS BOTTLE

Albert C. Meyer, Glenshaw, Pa., assignor to Glenshaw Glass Company, Glenshaw, Pa., a corporation of Pennsylvania

Application December 15, 1938, Serial No. 81,805

Term of patent 14 years

To all whom it may concern:

Be it known that I, Albert C. Meyer, a citizen of the United States, residing at Glenshaw, in the county of Allegheny and State of Pennsylvania, have invented a new, original, and ornamental Design for a Glass Bottle, of which the following is a specification, reference being had to the accompanying drawing, forming part thereof, in which Fig. 1 is a front elevational view of a glass bottle showing my new design; and Fig. 2 a top plan view thereof. The stippled area between the two bottom ribs of the bottle, as shown in Fig. 1 of the drawing, is repeated on the opposite side of the bottle.

The present application is a continuation in part of an application serially numbered D-78,141 filed June 29, 1938.

I claim:

The ornamental design for a glass bottle, as shown and described.

ALBERT C. MEYER.
